INVENTOR

Virginia Winston

UNITED STATES PATENT OFFICE

109,116

DESIGN FOR A TABLECLOTH OR SIMILAR ARTICLE

Virginia Winston, Jackson Heights, N. Y.

Application March 5, 1938, Serial No. 75,611

Term of patent 3½ years

To all whom it may concern:

Be it known that I, Virginia Winston, a citizen of the United States of America, residing in Jackson Heights, in the Borough of Queens, county of Queens, and State of New York, have invented a new, original, and ornamental Design for a Tablecloth or Similar Article, of which the following is a specification, reference being had to the accompanying drawing, forming part thereof, wherein,

The figure is a plan view of a tablecloth or similar article, showing my new design.

I claim:

The ornamental design for a tablecloth or similar article, substantially as shown.

VIRGINIA WINSTON.
